UNITED STATES PATENT OFFICE.

GENNARO A. AMATO, OF NEW YORK, N. Y., ASSIGNOR TO USNOICE REFRIGERATING CORPORATION, OF NEW YORK, N. Y., A CORPORATION OF NEW YORK.

DESIGN FOR AN ICELESS REFRIGERATOR.

61,009.

Specification for Design.

Patented May 30, 1922.

Application filed June 24, 1920. Serial No. 391,547. Term of patent 3½ years.

To all whom it may concern:

Be it known that I, GENNARO A. AMATO, a subject of the King of Italy, and resident of the city of New York (borough of Manhattan), county and State of New York, United States of America, have invented a new, original, and ornamental Design for an Iceless Refrigerator, of which the following is a specification, reference being had to the accompanying drawing, forming part thereof, wherein—

Figure 1 represents a perspective view of my complete iceless refrigerator, and

Figure 2 a perspective view of the same with the cover removed.

What I claim and desire to secure by Letters Patent is:

The ornamental design for an iceless refrigerator substantially as shown.

GENNARO A. AMATO.
